CASING FOR A DEODORIZER OR THE LIKE

Henry Worth, New York, N.Y., assignor to Dorchester Products, Inc., New York, N.Y., a corporation of New York

Filed Sept. 18, 1961, Ser. No. 66,743

Term of patent 14 years

(Cl. D16—2)

FIG. 4

FIG. 1

FIG. 2

FIG. 3

FIGURE 2 is a side elevational view thereof, the other side being of identical ornamental appearance;

I claim:

The ornamental design for a casing for a deodorizer or the like, as shown described.
